PROTECTIVE COVERING FOR VACUUM
CLEANERS

Wilfred O. Langille, Chester, N. J., assignor to The
Singer Manufacturing Company, Elizabeth,
N. J., a corporation of New Jersey

Application November 17, 1938, Serial No. 240,945

5 Claims. (CL 15—257)

This invention relates to vacuum cleaners of the ambulatory floor type and it has as its primary object to prevent vacuum cleaners from damaging furniture and other objects with which they inadvertently come into contact and also to prevent marring of the vacuum cleaners by reason of such contact.

Heretofore it has been customary to provide vacuum cleaners with relatively narrow rubber bumpers extending horizontally about the nozzles of the cleaners. While bumpers of that type prevented contact of the vacuum cleaner nozzle with substantially vertical surfaces, such for example as the base-board about a room and those portions of furniture which rest directly upon the floor, they did not prevent contact of the upper portions of the vacuum cleaner casing with those portions of furniture which are spaced slightly above the floor and under which it is not uncommon to attempt to push the vacuum cleaner. As is well understood, this inadvertent contact of the vacuum cleaner with articles of furniture and the like is destructive to both the furniture and the cleaner.

This invention has as an object to provide a protective covering for both the nozzle and the main casing of the vacuum cleaner which will prevent damage to both the cleaner and the objects with which the cleaner inadvertently comes into contact.

A further object of the invention is to provide a protective covering for vacuum cleaners which will snugly fit the curved contours of the cleaner, which may be removably secured thereto, and which will add to, rather than detract from, the appearance of the cleaner.

Another object is to provide a protective covering as above described which may be made and attached at a minimum of expense. This has been attained by constructing the covering of two major portions of moulded rubber, one adapted to cover the cleaner nozzle and the other adapted to overlie the first named portion and to extend upwardly therefrom and to cover the main casing of the cleaner.

Still another object of the invention is to provide improved and simplified means for removably securing the protective covering to the vacuum cleaner casing.

With the above and other objects in view, as will hereinafter appear, the invention comprises the devices, combinations, and arrangements of parts hereinafter set forth and illustrated in the accompanying drawings of a preferred embodiment of the invention, from which the several

features of the invention and the advantages attained thereby will be readily understood by those skilled in the art.

Fig. 1 is a side elevation of a vacuum cleaner embodying the present invention, portions of the handle bail and the dust bag being broken away.

Fig. 2 is a plan view of the cleaner shown in Fig. 1, with the handle bail complete but with the handle proper broken away.

Fig. 3 is a front elevational view of the cleaner shown in Fig. 1.

Fig. 4 is an inverted plan view of that portion of the protective covering which embraces the vacuum cleaner nozzle.

Fig. 5 is an inverted plan view of that portion of the covering which protects the main casing of the cleaner.

Fig. 6 is a sectional view taken substantially on the line 6—6 of Fig. 2 showing the means for securing the protective covering to the main casing.

Fig. 7 is a detail sectional view taken substantially on the line 7—7 of Fig. 2.

Fig. 8 is an enlarged sectional view taken substantially on the line 8—8 of Fig. 3.

Fig. 9 is a detail bottom view of a portion of the vacuum cleaner casing and a portion of the nozzle cover secured thereto showing the means employed for removably securing the two together.

Fig. 10 is a detail sectional view taken on the line 10—10 of Fig. 1.

Referring more specifically to the drawings, the invention is disclosed as embodied in a vacuum cleaner having a main frame or casing C comprising a body portion 1 including a transverse nozzle 2 and a hood or covering 3 which is secured to the body portion and overlies the usual fan-driving motor, not shown. The casing is mounted upon traction wheels 4 and is fitted with a handle H, consisting of a pivoted bail 5 and a handle proper 6 fitted therein, for manually propelling the cleaner over the surface to be cleaned. Secured to the rear end of the casing C is a dust bag 7, a portion only of which is shown.

As shown most clearly in Figs. 4 and 5, the improved protective covering comprises one main shoe-like section A of flexible moulded rubber adapted to be removably secured upon the transverse nozzle 2, and a tongue-like section B, also of flexible moulded rubber, which is adapted to extend upwardly from the section A and overlie the hood 3. The section A, in its normal unflexed condition, as shown in Fig. 4, is of gen-

erally rectangular shape and comprises hood-like end portions 8, an intermediate or face portion 9, which connects the end portions 8, and flexible leg portions 10 which are adapted to be secured to the sides of the body portion 1 of the main casing C. When the section A is applied to the cleaner, the portions 8 of the cover substantially enclose the end-portions of the nozzle except for the open under side thereof. The intermediate portion 9 of the section A is adapted to cover the forward face and a portion of the upper surface of the nozzle, as shown in Figs. 2 and 3. The legs 10 are provided at their lower edges with integrally formed L-shaped projections 11, which are adapted to engage the lower edge portions of the vertical side walls 12 of the body-portion 1 to help maintain the cover section A on the nozzle. At opposite sides of its center, the cover section A is formed with two upwardly extending ribs 13 between which the portion 14 of the cover section is reduced in both height and thickness. The tongue section B of the cover has a portion which fits between the ribs 13 and which overlies the reduced portion 14 as later will be described.

Secured to the hood 3 adjacent its forward lower edge, as by screws 15, (see Figs. 3 and 8) is a horizontally disposed sheet-metal anchor-plate 16 having its lower edge-portion 16a flared outwardly as shown most clearly in Fig. 8. The outwardly flared portion 16a of the anchor-plate is adapted to engage within channels 17 moulded in the lower portion of the cover section A at opposite sides of the reduced mid-portion 14, thereby to prevent the cover section A riding up on the nozzle. The screws 15 also serve to secure the forward end of the hood 3 to the nozzle.

After the cover section A has been secured to the nozzle, the tongue-section B is applied to the hood 3 with the lower end thereof overlying the section A and secured to the nozzle. As shown most clearly in Figs. 5 and 6, the upper end of the tongue-section has moulded therein a sheet-metal hook-like element 18 which is adapted to engage within an aperture 19 formed in the hood 3, thereby to hold the upper end of the section in contact with the hood. The lower end of the tongue-section is formed with a groove 20 into which the lower edge of the plate 16 is adapted to engage, as shown in Fig. 6, thereby to secure the lower end of the tongue-section to the cleaner. Adjacent its lower end the section B is formed on its inner face with a transverse channel 21 adapted to receive the reduced portion 14 of the section A. As shown by Fig. 6, the combined thicknesses of the portion 14 of section A and the section B adjacent the channel 21 equal the thickness of the adjacent portions of the tongue-section and therefore the outer curved contour of the tongue-section is smooth and unbroken. Intermediate its ends, the section B is formed with a substantially rectangular opening 22 adapted to receive and frictionally hold a metal grill 23 which prevents accidental contact with an electric illuminating lamp L located therebehind.

To hold the mid-portion of the cover section B in contact with the hood 3, the cover section is formed with inturned hook-like extensions 24 and 25 located adjacent the upper and lower ends, respectively, of the opening 22 therein, and similar extensions 26 and 27 at the opposite sides of said opening. These hook-like extensions project through a substantially rectangular opening 28 in the hood 3 and engage the inner face of

the hood, as shown most clearly in Figs. 6 and 7, to secure the cover section B thereto.

The sections A and B are preferably provided with surface ornamentation in the nature of beads and ribs which improve the appearance of the cover and therefore add to the attractiveness of the cleaner as a whole.

In certain makes of vacuum cleaners the hood which overlies the fan-driving motor is formed with one or more apertures to permit radiation of the heat which is generated by the motor. Such apertures are shown in Figs. 2 and 6 as comprising slots 30 separated by a central rib 31. To the end that the cover section B will not interfere with such radiation, it is formed with an opening 32 which overlies the slots 30 in the hood when the protective covering is secured upon the cleaner casing.

From the foregoing it will be perceived that this invention has provided a protective covering which may readily be applied to or removed from a vacuum cleaner and when applied thereto will protect both the cleaner and any object with which the cleaner may inadvertently come into contact during normal operation of the cleaner.

Having thus set forth the nature of the invention what I claim herein is:

1. In combination with a vacuum cleaner having a casing including a nozzle and a hood, a two-part protective covering of relatively soft moulded material comprising one preformed moulded section adapted to be secured horizontally about said nozzle, said section being formed substantially mid-way between its ends with a portion reduced in both width and thickness, and a second preformed moulded section adapted to be secured to said casing and to extend from adjacent the lower edge of said nozzle upwardly to overlie said nozzle and hood, said second section having adjacent its lower end and on its inner face a transverse channel adapted to receive the reduced portion of said first section, whereby the combined thickness of the overlapped portions of the two sections equals substantially the major thickness of the first section, and means for removably securing said sections to said casing.

2. In combination with a vacuum cleaner having a casing including a nozzle and a hood, a horizontally disposed sheet-metal anchor-strip secured to the outer surface of the forward wall of said nozzle, said anchor-strip having an outwardly flared and downwardly extending lower edge portion, a protective covering of relatively soft moulded material comprising a first section extending horizontally about said nozzle and having portions at its ends adapted to grip the side walls of said casing, said section also gripping the end portions of said anchor-strip to hold the section on the nozzle, and a second section overlying the mid-portion of said first section and engaging the flared portion of said anchor-strip substantially midway between its ends, said second section extending upwardly from the first section and overlying said hood, and means for securing the upper end of said second section to said hood.

3. A protective covering for a vacuum cleaner casing having a nozzle and a hood comprising a first cover section having hood-like end portions adapted to embrace the end portions of the cleaner nozzle and a mid-portion, reduced in both width and thickness, connecting said end portions and adapted to cover the forward face and a

portion of the upper face of the nozzle, a second cover section having a portion overlying and interlocking with the reduced mid-portion of the first cover section and extending transversely thereof and adapted to overlie the hood portion of the cleaner, and means carried by said cover sections and adapted to cooperate with portions of the vacuum cleaner to secure the protective covering to the cleaner casing.

4. A protective covering for a vacuum cleaner casing having a nozzle and a hood, said hood being provided with an aperture adapted to permit passage of light from a lamp located within said casing, said covering comprising a shoe-like section of relatively soft resilient moulded material adapted to substantially embrace the cleaner nozzle, a tongue-like section of relatively soft resilient moulded material extending upwardly and transversely of the first mentioned section and adapted to overlie the hood portion of the casing, said tongue-like section being provided with an aperture aligned with the aperture

5 in said hood and adapted to receive and hold a lamp-protecting grill, and means carried by said cover sections and adapted to cooperate with portions of the vacuum cleaner casing to secure the protective covering to the cleaner casing.

5. A protective covering for a vacuum cleaner casing having a nozzle and a hood comprising a first cover section of moulded rubber having end portions adapted to embrace the end portions of the cleaner nozzle and a mid-portion connecting said end portions and adapted to substantially cover the forward and upper faces of the nozzle, said mid-portion being locally reduced in width and thickness, a second cover section having a portion embracing the reduced portion of the first cover section and extending upwardly therefrom and adapted to overlie the hood portion of the cleaner, and means carried by said cover sections and adapted to cooperate with portions 20 of the vacuum cleaner casing to secure the protective covering to the casing.

WILFRED O. LANGILLE.
